UNITED STATES PATENT OFFICE.

HENRY WILLIAM CLOTHIER, OF WALLSEND, ENGLAND, ASSIGNOR TO A. REYROLLE & COMPANY LIMITED, OF HEBBURN-ON-THE-TYNE, ENGLAND.

ELECTRIC SWITCH-GEAR.

1,357,847.

Specification of Letters Patent.

Patented Nov. 2, 1920.

Application filed December 2, 1918. Serial No. 265,018.

To all whom it may concern:

Be it known that I, HENRY WILLIAM CLOTHIER, a subject of the King of England, and residing at Wallsend, Northumberland, England, have invented certain new and useful Improvements in Electrical Switch Gears, of which the following is a specification.

This invention relates to electrical switch gear and has particular reference to oil-break switch gear for high voltage alternating current work such switch gear being of the type comprising two main portions one fixed and the other removable for isolating purposes.

It is well known that the oil containing tanks or vessels for such switch gear are subjected to sudden heavy shocks or stresses which occur when large power circuits are broken and many suggestions have been made as to making the tanks capable of withstanding these forces.

The primary object of the present invention is to simplify and cheapen the construction of switch gear of this type by the provision of a tank which is capable of withstanding the shocks above mentioned and also acts as the mechanical support of the gear as a whole thus obviating the necessity for the usual frame work.

In switch gear to which this invention is applicable there are three oil-containing vessels one, generally central containing the main switch, another accommodating the bus bars, and the third containing the terminals for the incoming cables and the transformers. The vessels containing the bus bars and transformers are sometimes compound filled instead of containing oil.

Usually these tanks are separate structures and are supported by a frame work the two side tanks often being smaller than the central tank and mounted in brackets forming part of the frame.

According to the present invention the three tanks are integral and form a self-supporting structure the two side tanks forming reinforcements for the walls of the central tank where the main break occurs and which consequently is subjected to the heaviest stresses.

The tank is not merely self-supporting but it also forms the structural foundation or base of the whole switch gear by carrying

the removable portion of the gear which rests upon the tank and not upon an independent frame work or stand. The strength of the tank is thus used for two purposes namely to enable it to withstand the stresses set up on the breaking of the circuit and also to enable the tank to be utilized as the mechanical support of the whole gear.

The improved tank may be made in various ways, for instance it may be of cast metal or it may be of sheet metal riveted or welded and it may be provided, if desired, with a flexible or other inner tank or with other known arrangements to lessen the effect of the internal stresses.

In one construction of switch gear according to this invention suitable say for three-phase work, the tank is formed of one main rectangular vessel divided by partitions into three compartments forming three separate oil-containing tanks. The central compartment contains the main switch and is further strengthened by the provision of transverse webs forming part of or secured to the side walls and serving to separate the phases. Near each end of the central tank there may be transverse partitions which act as additional strengthening members and also serve to form two small end chambers which may contain for example gear for lifting the removable portion when the switch has to be isolated. When these transverse partitions are provided the central compartment where the main break takes place is backed up or reinforced at each side by a compartment containing oil and this arrangement materially reduces the effects of the shocks on the walls of such central compartment.

Lugs or brackets are provided within the central compartment to receive the holding down bolts for securing the removable portion of the gear and other lugs are provided in the side compartments for the support of the apparatus contained therein.

One of the side compartments is intended for the bus bar connections and may be furnished with compound filled boxes or chambers at its ends or side to contain the connections between the bus bars of adjacent units or panels. The other side compartment is fitted externally with the usual form of dividing box, compound filled, for the entrance of the cores of a multi-core cable.

Within this compartment are contained the potential and current transformers with their necessary connections.

The removable portion of the switch gear 5 is mounted on what may be regarded as the cover for the tank preferably having a flanged edge resting on and supported by the tank. It comprises the main switch and the mechanism for opening and closing it and 10 connections to auxiliary or isolating contacts co-operating when the removable portion is in its normal working position on the tank, with other contacts suitably supported in the side compartments of the tank.

15 In the accompanying drawings which illustrate one construction of switch gear according to this invention,

Figure 1 is a plan of the tank.

Fig. 2 is a vertical section on the line 2—2 20 of Fig. 1 showing the removable upper portion of the gear and also the fixed portion contained in the tank.

Fig. 3 is a section on the line 3—3 of Fig. 1 with the fixed portions of the gear in position, and

25 Fig. 4 is an elevation of the removable portion of the gear.

The tank A is divided by partitions A' and A² into three compartments. The central compartment A³ contains the main oil-break switch B which is carried by the removable lid-like structure C. The central compartment is strengthened by the provision of transverse webs A⁴ which serve to 30 separate the phases. In the construction shown by way of example the tank is only provided with one pair of these transverse webs thus making it suitable for two phases but it will be understood that for three 35 phases another pair of webs might be provided thus dividing the central compartment into three portions instead of two.

40 The right hand compartment A⁵ of the tank contains a potential transformer D shown in chain lines in Fig. 2 and the incoming cable E is brought through some usual form of cable dividing box F attached to the wall of the tank and ends in a connection E' in the compartment A⁵. Lugs or 45 brackets A⁶ are provided on the walls of the compartment A⁵ upon which rests a plate E² carrying in a suitable insulator, a connection between the cable connection E' and the isolating contact G carried by the lid C and 50 connected with one pole of the main switch.

55 The left hand compartment A⁷ accommodates the bus bar connections H which may enter through compound filled boxes H' (Fig. 1) at each end of the compartment or 60 alternatively if the space between one unit or panel and another is limited from the side of the tank as shown in chain lines in Fig. 1. The connections between the bus bars and the main switch are through isolating plug 65 connections J the fixed portions of these con-

nections being carried on a bracket E³ supported by lugs A⁸ on the walls of the compartment.

The connections between the plug isolating contacts and the main switch are in compound filled chambers C' and C² forming the removable lid-like portion of the switch gear which also carries the main switch. This portion of the gear is shown in elevation separately at Fig. 4 the handle for operating the main switch being indicated at K. It is however to be understood that the details of the main switch and its mechanism do not in themselves form part of the present invention and are therefore not described.

70 The central compartment A³ is provided with lugs A⁹ some of which may accommodate holding down bolts A¹⁰ for the removable upper portion of the switch gear. 75

Fig. 1 the central compartment A³ is shown provided with transverse partitions A¹¹ near each end. These act to strengthen the walls of the central compartment and in the space between the outer walls of the tank 90 A and the partitions A¹¹ lifting gear for the upper portion of the switch gear may be accommodated.

95 It is to be noticed that the tank A is a self-supporting structure and carries the removable portion of the switch gear which forms a lid-like cover to the tank.

100 Although the tank is shown as one main vessel divided into three compartments of equal depth other constructions may be used providing that the three portions of the tank form an integral structure and constitute the supporting part or foundation of the gear. For instance the tank may be a casting with 105 side extensions or chambers at its upper portion such extensions constituting the side tanks which may or may not be separated by partitions from the central portion.

110 What I claim as my invention and desire to secure by Letters Patent is:—

1. In electric oil-break switch gear a tank for oil or other insulating liquid comprising a central portion to contain the main switch and two side tanks or chambers forming reinforcements for the walls of the central portion, said side tanks being adapted to contain the bus bar or other fixed connections of the switch gear, the tank as a whole being self-supporting and carrying the removable portion of the gear which rests 115 upon it.

120 2. In electric oil-break switch gear the combination of a tank consisting of a main vessel divided by partitions into three compartments forming three separate tanks a lid-like cover supported solely by the tank upon which it rests, bus bar or other fixed connections in the outer compartments, a main switch carried by the cover and normally contained in the central compartment, 125 130

and isolating contacts also carried by the cover and coöperating with the fixed connections in the outer compartments substantially as set forth.

- 5 3. In electric oil-break switch gear the combination of a tank consisting of a main vessel divided by partitions into three compartments forming three separate tanks, transverse webs strengthening the partitions, a lid-like cover supported by the tank, bus bar or other fixed connections in the outer compartments, a main switch carried by the cover and normally contained in the central compartment, and isolating contacts also carried by the cover and coöperating with the fixed connections in the outer compartments substantially as set forth.
- 10 4. In electric oil-break switch gear the

combination of a tank consisting of a main vessel divided by partitions into three compartments forming three separate tanks, a lid-like cover supported by the tank, bus bar or other fixed connections in the outer compartments, brackets fixed in the outer compartments, contacts for isolating connections supported on the brackets, connections between such contacts and the fixed connections in the outer compartments, a main switch carried by the cover and normally contained in the central compartment and isolating contacts also carried by the cover and coöperating with the contacts carried by the brackets substantially as set forth.

In testimony whereof I have signed my name to this specification.

HENRY WILLIAM CLOTHIER.
